UNITED STATES PATENT OFFICE.

FRIEDRICH ALLENDORF, OF FRANKFORT-ON-THE-MAIN, GERMANY, ASSIGNOR TO
JACOB ROSENBERG, OF NEW YORK, N. Y.

FUEL-SAVING DEVICE FOR STOVES, RANGES, OVENS, AND THE LIKE.

Application filed March 14, 1924, Serial No. 699,357, and in Germany March 16, 1923.

This invention relates to a fuel saving device for use in stoves, kitchen ranges or like heating devices using solid fuel, and its purpose is to save fuel by the use of the 5 fuel saving device in the fireplace or grate, in order to reduce the existing combustion space and cause a gasification of the fuel when sufficient heat has been produced, and consequently to attain a complete combustion 10 of the fuel.

The fuel saving device consists of perforated plates of fire bricks or like refractory material, which are adapted to be arranged to form a box-like container without 15 a bottom or front. By inserting the device in a range or fireplace the bottom of the container is constituted by the grate and the front by the fire door, if such exists.

In order that the invention may be more 20 readily understood reference will be made to the accompanying drawing illustrating, by way of example, one form of construction thereof:—

Figure 1 is a perspective view of the 25 device, and

Fig. 2 is a like view of a modification.

The device is constituted by two side walls *a* and *b*, a rear wall *c* and a slidable cover-plate *d*, all said parts being made of refractory material. The cover or top plate *d* may be replaced by any other form of cover. The bottom is formed by the existing fire grate *e*. The side walls *a* and *b* and the rear wall *c* are provided with slots, perforations or nozzle-shaped openings *f* for the 30 passage of air. If desired such perforations or nozzle shaped openings may also be provided in the sliding cover *d* in order to increase the air supply. Each wall *a* and *b* is provided at its upper end with parallel 35 projections forming a groove *g* in which the slide *f* is guided; the latter may advantageously be provided with an appropriate locking device (not shown) to prevent its 40 accidental displacement during supply of fuel to the grate within the space formed by the walls *a*—*b*—*c*—*d*.

The slide *d* is cut away at the front at *h* 45 to form an exit opening for the products of combustion and has a knob *i* for engagement by a hook or the like in order to move it in or out. The cut-away portion is provided so that a pot or the like may be heated by direct flame when the slide *d* 50 is closed.

In the event of the existing combustion space being so large that too great a space is left behind the rear wall *c*, an auxiliary unperforated vertical wall or false back *k* may be provided at such a distance from 60 the wall *c* that a narrow channel is formed between them.

The slide is closed when the ignition temperature is reached and the combustion gases there formed are ignited by the air entering 65 through the wall openings and burned, which keeps up the further fuel gasification and enables a complete utilization of the fuel.

The whole device can be easily adapted to 70 any existing or desired size of range or stove, and may also be provided with double walls, as in Fig. 2, in which case the space between these walls *a*—*m* and *b*—*m* may 75 serve as an air-supply and preheating channel. If desired, the combustion air may be supplied by means of a blower *y* or the like.

What I claim is:—

1. A fuel saving device for stoves, or fire-places comprising an open fronted box-like 80 structure consisting of three perforated walls of refractory material adapted to be placed upon the grate of an existing stove, and a cover plate slidable in the upper ends of the two side walls, substantially as de- 85 scribed.

2. A fuel saving device for stoves, or fire-places comprising an open fronted box-like 90 structure consisting of three perforated walls of refractory material adapted to be placed upon the grate of an existing stove and a perforated cover plate with a semi-circular cut-away portion, slidable in the upper ends of the two side walls substantially as de- 95 scribed.

3. A fuel saving fireplace or stove com- 100 prising a grate, an open fronted box-like structure consisting of three perforated walls of refractory material adapted to be placed upon the grate of an existing stove, and a cover plate slidable in the upper ends of the two side walls and an unperforated vertical wall behind the rear wall of the box-like structure substantially as described.

4. A fuel saving device for stoves, or fire- 105 places comprising an open fronted box-like structure consisting of three perforated walls of refractory material adapted to be placed upon the grate of an existing stove, a cover plate slidable in the upper ends of 110

the two side walls and a blower to supply air for combustion substantially as described.

5. A fuel saving device for stoves and the like comprising an open-fronted box-like structure consisting of perforated walls for resting with their lower edges on the grate of a stove and the like, and a movable cover having an opening for the gases generated in said box.
- 10 6. A fuel saving device for stoves and the like comprising an open-fronted box-like structure, said open front arranged to be closed by the door of the stove in which the

device is placed and consisting of three vertical double walls, each wall having perforations between the space therein and the interior of said box, and a removable cover for said walls, having an opening therein for the products of combustion, whereby combustion air will pass through the grate between said double walls and be preheated before passing through the perforations into the interior of said device. 15

In testimony that I claim the foregoing as my invention, I have signed my name.

FRIEDRICH ALLENDORF. 20
